UNITED STATES PATENT OFFICE.

JULIUS JEIDEL, OF CHICAGO, ILLINOIS.

SPRING WHEEL.

1,426,741.

Specification of Letters Patent. Patented Aug. 22, 1922.

Application filed October 7, 1921. Serial No. 506,109.

To all whom it may concern:

Be it known that I, JULIUS JEIDEL, a citizen of the United States, residing at Chicago, in the county of Cook and State of Illinois, have invented a certain new and useful Improvement in Spring Wheels, of which the following is a specification.

My invention relates to spring wheels and one of the objects of the invention is to provide a construction which will utilize all of the springs all the time, that is, a construction such that all of the springs, practically speaking, will be effective for all positions of the wheel. Another object is to provide friction means interposed between the hub and the felloe, capable of operating as a shock absorber. Still another object is to provide a construction by which the parts may be kept thoroughly lubricated at all times and without any attention on the part of the user except at long intervals.

I obtain these objects by the mechanism illustrated in the accompanying drawings in which—

25 Figure 1 is a side elevation of the complete wheel, the near cover plate being removed and certain parts being in section to better reveal the construction.

Figure 2 is a horizontal axial section of the wheel.

Figure 3 is an outside elevation of the wheel, part of the near cover plate and hub cap being broken away to reveal the internal construction.

35 Figure 4 is a fragmentary perspective view showing the arrangement of the springs and friction leaves.

Figure 5 is a perspective view of a spring seat.

40 Figure 6 is a perspective view of a modified form of spring having an anti-friction roller at its free end.

Like numerals refer to like parts throughout the several views.

45 In the form shown in the drawings, the wheel has a hub 1 adapted to bear on the axle 2 in the ordinary manner. On the outside it has an integral flange or disc 4 which is bolted to a member 6 which has a cylindrical central aperture to enable it to fit over the hub 1, and in a sense becomes a part of it. Consequently the parts 1 and 6 may be regarded as composing the hub of the wheel. Radiating from the hub are 50 spokes 10.

Fastened to the edges of the spokes are springs 12. These are the principal springs of the wheel and they extend approximately radially, as shown. They are illustrated in the form of leaf springs the plane whereof is at right angles to the plane of the wheel. They are fastened at their inner ends, in the present case by blocks 14 bolted to the hub. The springs are free at their outer ends where they bear in seats 16 fastened to the rim 18 of the wheel. According to the present design these seats are in the general form of an arch and have feet 20 by which they may be riveted or otherwise fastened to the rim. This, however, is not essential, the chief point being that they are arranged approximately radially and that their sides slope with respect to the nearest radius. In the design shown, the seats slope in two opposite directions from the point 25 where the free ends of the springs normally rest. In other words, they are cupped or are doubly sloped so that when the co-operating spring moves radially in either direction from the normal position, 80 the strain of the spring will be increased. By properly reducing friction the springs freely slide on the seats and always tend to come to rest at the center or depressed portion of the seat, thus tending to hold the hub in central position. In the form shown in Figures 1 and 5 the free ends of the springs are rounded and means are provided for lubricating them. In the form shown in Figure 6 the free end of the spring is 90 provided with an anti-friction roller 27 for enabling the parts to act freely.

Fastened to the rim 18 are two annular plates 30. These enclose the outer ends of the springs and the outer ends of the spokes, one of their functions being to prevent end-thrust, that is relative movement of the hub and rim in an axial direction. The springs 12 and seats 16 are located between them. Friction members 40 are arranged radially on each side of each spoke. They are here illustrated in the form of flat bars of fibre or other appropriate material. They are fastened at the inner end to the sides of the spokes and at the outer end they 100 are yieldingly held spaced a slight distance from the spokes by helicoidal compression springs 42 which are mounted in apertures formed at the ends of the spokes. The springs are arranged parallel to the axis of 110

the wheel and their purpose is to press the ends of the friction elements or fingers 40 against the inside of the ring-like plates 30 to create friction when the parts move relative to each other. This friction yieldingly resists movement of the hub relatively to the rim and hence the friction elements serve as shock absorbers and prevent too rapid recoil when the main springs 12 have been strained.

It is desirable to enclose the co-acting parts in oil, and for this purpose I provide cover plates 50 which extend to the rim of the wheel and are apertured at the center to accommodate the hub elements 1, 6. In order to form a tight closure at the inner rim and at the same time permit relative movement between the hub and the rim, I provide washers 52, mounted in the hub in such manner as to permit the cover plates to pass between them. The inner cover plate and the adjacent washers are held in position by a disc 54 which is bolted to the hub and corresponds with the flange 4 of the hub element 1.

The operation will now be readily understood. When the parts are assembled the wheel is partially filled with lubricating oil, the purpose being to permit the springs 12 to slide freely upon the seats 16. If, now, in traveling, the rim of the wheel strikes an obstacle and tends to rise to pass over it the seats 16 in rising will act like cams to press the ends of the springs 12 toward the adjacent spokes. This is true of all the spring seats except two, or a few which are temporarily in approximately horizontal position. The springs which are approximately horizontal and which are temporarily on the under side of their seat will, of course, have no effect in supporting the hub at the moment, but all the others will act in the manner stated both above the hub and below it. Thus all of the springs, practically speaking, are effective all of the time, and thus they may be of much lighter weight and material than in those wheels where only a few of the springs are operative at a time.

Another advantage of my construction is that it is noiseless, not only because it is usually filled with oil but because the fibre fingers which act as friction elements are naturally soundless under such condition. They merely rub upon the side plates and there is no cause for any clicking or similar noise. Another advantageous feature of my construction is that when the springs are strained the pressure is always in the same direction—that is, towards the adjacent spoke. This is much better than in those cases where the spring is strained first on one side and then on the other side of a normal line of rest. By exerting pressure

always in the same direction the life of the springs is greatly increased.

Having thus described my invention what I claim as new and desire to secure by Letters Patent is:

1. A spring wheel having a hub and a felloe, one having springs arranged approximately radially and the other having seats, the springs being fastened at one end and free at the other, the free ends of the springs seating in said seats, and the seats having sloping, nonradial sides whereby the engaged ends of the springs tend always to return to the bottom of the seats and thereby hold the hub concentric with the felloe.

2. In a spring vehicle wheel, the combination, with the hub and felloe, of springs extending approximately radially and fastened to the hub of their inner ends, and seats fastened to the felloe and adapted to engage the outer ends of the springs, each seat being a concavity the sides whereof are sloping and rise on either side from the bottom of the concavity whereby they serve as a pair of cams tending always to return the engaged end of the co-operating spring to the bottom of the concavity and thus centralize the hub.

3. A spring wheel having a hub and a felloe, springs extending approximately radially and fastened to the hub at their inner ends, and seats fastened to the felloe, the springs contacting with the seats always at their outer ends, and the sides of the seats being oblique whereby when the end of the spring moves either towards or away from the center of the wheel its tension will be increased.

4. A spring wheel having a hub and a felloe, and springs interposed between them for resiliently supporting the hub, the hub having radiating spokes and the felloe having a side plate arranged in the plane of the wheel, and friction members fastened to the sides of the spokes and adapted to rub on said side plate to check the recoil and absorb shocks.

5. A spring wheel having a hub and a felloe, and springs interposed between them for resiliently supporting the hub, the hub having radiating spokes and the felloe having side plates on both sides of the hubs, friction members arranged radially and fastened at their inner ends to the sides of the spokes, and compression springs adapted to press the outer ends of the friction members against said side plates to thereby create friction when the hub moves relatively to the side plates in the plane of the wheel.

In witness whereof, I have hereunto subscribed my name.

JULIUS JEIDEL.
